UNITED STATES PATENT OFFICE.

SAMUEL V. KENNEDY AND CHARLES S. SHARP, OF AUBURN, NEW YORK,
ASSIGNORS TO D. M. OSBORNE AND COMPANY, OF AUBURN, NEW YORK,
A CORPORATION OF NEW YORK.

DISK HARROW.

SPECIFICATION forming part of Letters Patent No. 760,742, dated May 24, 1904.

Application filed November 30, 1903. Serial No. 183,188. (No model.)

To all whom it may concern:

Be it known that we, SAMUEL V. KENNEDY and CHARLES S. SHARP, citizens of the United States, residing at Auburn, in the county of Cayuga and State of New York, have invented 5 certain new and useful Improvements in Disk Harrows, of which the following is a specification.

The object of our invention is to provide a 10 scraper for disk harrows that is simple in construction and effective in dislodging any matter that may adhere to and clog the disks.

Referring to the drawings, Figure 1 is a rear 15 view of one of the gangs of disks of a disk harrow, showing our improved scraper mounted thereon. Fig. 2 is an end view of Fig. 1. Fig. 3 is an enlarged view of the rocking lever and the rotary lever connected parts for operating the scrapers. Fig. 4 is an enlarged 20 view showing the method of mounting the scraper, part of the scraper-blade being broken away. Figs. 5, 6, and 7 are details.

A represents the frame-bar of a disk harrow, to which is suspended a gang of disks 25 mounted upon an axle and spaced in the ordinary manner.

B is a scraper-bar mounted in slots b^3 in brackets $a\ a'$ on the frame-bar A.

The scrapers C are preferably made of sheet-30 steel, their lower ends being beveled to secure a better and more effective cleansing of the disks. Each scraper has a slot b in its upper end through which the scraper-bar B is passed, the latter having at proper intervals portions 35 cut out from its upper edge forming notches in which the upper ends of the slots of the scrapers rest. Castings D are rigidly bolted to the scraper-bar B, and projecting from them integral therewith and parallel with the scraper-40 bar are arms b' , which pass through the slots in the scraper-blades. Between shoulders b^2 on the castings D and the scraper-blades C are 45 springs c, holding the latter in against lips or offsets c' , which engage with the lower ends of the slots in the scraper-blades.

The scraper-blades when in a normal position are not in direct contact with the faces of the disks, but must be moved into opera-

tive contact before they are rocked to cleanse the disks of adhering matter. Consequently 50 the scraper-bar B has a longitudinal as well as a rocking movement, which it receives through the operation of levers, as will now be described.

For rocking the gang of scrapers to clean 55 the disks a lever E is provided and is rigidly attached to the scraper-bar B. A rotary lever F is journaled in suitable bearings on the lever E, its upper end being bent at right angles to form a handle and its lower end bent 60 similarly with an eye formed at its extremity in which is hooked a link e, an end of said link passing through an eye f on the bracket a', the play of the link in one direction being regulated by adjustable nuts e'. It will be 65 seen that notwithstanding the levers E and F are connected they do not interfere one with the other at any time in their movements.

To operate our device to clean the disks, the lever F is rotated, as shown in Fig. 3, acting as a 70 lever whose fulcrum is the point of connection with the link e. The scraper-bar is moved horizontally, carrying the scraper-blades into forcible contact with the concave faces of the disks. The full movement of the lever F carries the 75 hook end of the link e above the horizontal plane of the eye f on the bracket a' and the lower bearing f' of the lever F, as shown in Fig. 3. The back pressure of the scraper-blades and also the springs c tends to keep the lever 80 locked in this position. The lever E is then rocked, swinging the scraper-blades across the faces of the disks from center to periphery and the reverse, as shown in Fig. 2, completely removing any adhering material. By rotating 85 the lever F to its normal position the back pressure of the scraper-blades and the springs c will force the scraper-bar and scrapers back to their inoperative position.

Having thus described our invention, what 90 we claim is—

1. In a disk harrow, the combination with a gang of rotary disks, of a frame supported thereon, a sliding and rocking scraper-bar supported by the frame, a series of scraper-blades mounted on the bar, means controlled 95

by the driver for sliding the bar endwise to throw the scrapers into contact with the disks, and separate means also under the driver's control for rocking the bar to cause the scrapers 5 to sweep across the disks.

2. In a disk harrow the combination with a gang of rotary disks, of a frame supported thereon, a rocking scraper-bar supported by the frame, a series of slotted scraper-blades 10 mounted on the bar, and notches in said bar with which the slots of the scrapers engage.

3. In a disk harrow the combination with a gang of rotary disks, of a frame supported thereon, a rocking scraper-bar supported by 15 the frame, notches in said bar, a series of slotted scraper-blades through which the bar passes, said slots and notches engaging to hold the upper ends of the scraper-blades in place.

20 4. In a disk harrow the combination with a gang of rotary cutting-disks, of a rocking scraper-bar having notches therein, slotted scraper-blades mounted thereon, the upper ends of the slots engaging with the notches 25 in the scraper-bar, and castings on said bar having arms projecting through the slots in the scraper-blades and engaging therewith.

5. In a disk harrow the combination with a gang of rotary disks of a rocking scraper-bar 30 having notches therein, slotted scraper-blades mounted thereon, castings on said bar having arms projecting through the slots in the scraper-blades and engaging therewith, and springs on said arms bearing against the 35 blades.

6. In a disk harrow the combination with a gang of rotary disks of a rocking scraper-bar having notches therein, slotted scraper-blades, the upper ends of the slots engaging the 40 notches in the scraper-bar, castings on said bar having arms projecting through the slots in the scraper-blades, catches on said arms engaging with the lower ends of the slots, and springs on the arms bearing against the 45 scraper-blades to hold the latter in normal working position.

7. In a disk harrow, the combination with a

gang of rotary disks, of a rocking and sliding scraper-bar, slotted scraper-blades mounted thereon, a lever for sliding the bar endwise to 50 throw the scraper against the disks, and a separate lever for rocking the bar to throw the scrapers across the faces of the disks.

8. In a disk harrow, the combination with a gang of rotary disks, of a sliding and rocking 55 scraper-bar, slotted scraper-blades mounted thereon, a lever for moving said scrapers toward the disks, and a separate lever for rocking the scraper-bar to swing the scraper-blades across the faces of the disks and in contact 60 therewith.

9. In a disk harrow the combination with a gang of rotary disks, of a frame supported thereon, brackets on the frame, a rocking scraper-bar movable in said brackets, a series 65 of scrapers carried by the scraper-bar, an actuating-lever on said bar, a rotating lever journaled on the actuating-lever, and a link connecting the rotating lever with the bracket.

10. In a disk harrow the combination with a 70 gang of rotary disks of a scraper-bar, scraper-blades mounted thereon, an actuating-lever, and a rotating lever for moving the scraper-blades into engagement with the disks.

11. In a disk harrow the combination with a 75 gang of rotary disks, of a scraper-bar, a series of scrapers mounted thereon, an actuating-lever to swing said scrapers, a rotating lever journaled thereon and operated to move and lock the scrapers into engagement with the 80 disks.

12. In a disk harrow the combination with the disks, of a scraper-bar, a series of slotted scrapers mounted thereon, an actuating-lever, a rotating lever journaled thereon and a link 85 connecting said rotating lever with the frame.

In testimony whereof we hereunto set our hands, this 19th day of November, 1903, in the presence of two attesting witnesses.

SAMUEL V. KENNEDY.
CHARLES S. SHARP.
